(57) **CLAIM**

The ornamental design for a coin counting device, as shown and described.

DESCRIPTION

FIG. 1 is a front perspective view of a first embodiment of a counting device showing my new design;
FIG. 2 is a bottom perspective view of the coin counting device of FIG. 1;
FIG. 3 is a front view of the coin counting device of FIG. 1;
FIG. 4 is a back view of the coin counting device of FIG. 1;
FIG. 5 is a left view of the coin counting device of FIG. 1;
FIG. 6 is a right view of the coin counting device of FIG. 1;
FIG. 7 is a top view of the coin counting device of FIG. 1;
FIG. 8 is a bottom view of the coin counting device of FIG. 1;
FIG. 9 is a front perspective view of a second embodiment of a coin counting device showing my new design;
FIG. 10 is a bottom perspective view of the coin counting device of FIG. 9;

FIG. 11 is a front view of the coin counting device of FIG. 9;
FIG. 12 is a back view of the coin counting device of FIG. 9;
FIG. 13 is a left view of the coin counting device of FIG. 9;
FIG. 14 is a right view of the coin counting device of FIG. 9;
FIG. 15 is a top view of the coin counting device of FIG. 9;
and,

FIG. 16 is a bottom view of the coin counting device of FIG. 9.

The broken lines shown in the drawings represent portions of the coin counting device that form no part of the claimed design.
